UNITED STATES PATENT OFFICE.

FRANK AMOS JOHNSON, OF DUNELLEN, NEW JERSEY.

FEED DEVICE FOR STENCIL-CUTTING MACHINES.

1,138,759.

Specification of Letters Patent. Patented May 11, 1915.

Application filed April 5, 1913. Serial No. 758,997.

To all whom it may concern:

Be it known that I, FRANK AMOS JOHNSON, a citizen of the United States, and a resident of Dunellen, in the county of Middlesex and State of New Jersey, have invented a new and useful Feed Device for Stencil-Cutting Machines, of which the following is a specification.

My invention relates to a device for giving a variable feed to the stencils of a stencil-cutting machine in order that the normal spacing between the letters of certain lines may be reduced and additional characters put in those lines.

In the accompanying drawings I have shown so much of an Elliott stencil-cutting machine as is necessary to illustrate my invention.

Figure 1 is a front elevation; Fig. 2 is a plan; Figs. 3 and 4 are cross sections on the lines 3—3 and 4—4 of Fig. 1 respectively.

In the large number of these machines which are in use provision is made for putting twenty-seven characters and spaces in a line. It frequently happens that three or four additional characters need to be put into a line. This is sometimes accomplished by throwing out the machine feed and by feeding the stencil by hand, gaging the movement by the eye. This is slow and unsatisfactory. Quite a number of machines have been altered and a finer or closer feed put on them; but where this is done they cannot be changed back to the normal feed and all the lines of all the stencils which are cut have a very narrow "land" between the letters, thereby greatly weakening the stencil. By my device the normal spacing of the letters is obtained for lines which do not exceed the normal length. If one additional character is needed to be inserted in a line the machine may be set to put it in—the normal spacing between all the letters being reduced a very little; and so on for two, three, four or five additional characters. Only those lines which need to be reduced below normal letter spacing are changed and the spacing of each line is reduced the least possible amount that is necessary to accommodate the letters to be put into that line. The stencils are, therefore, as a whole, much stronger than they would be if all the lines were closely letter spaced. The change is effected almost instantly, so that in cutting a thousand stencils it might happen that only ten or a dozen lines would need to be

reduced in letter spacing below the normal, the change would be made for these lines without appreciable loss of time and the remaining lines normally letter spaced.

In the Elliott machine there is a main frame 1, which carries a revolving die wheel 2, which is provided with a series of punches 3. The movements of the die wheel are controlled by an index wheel 4, which is supported by a downward and forwardly projecting portion 5 of the frame. The front of the frame is so formed that it may be cut away, leaving four ears or clips which serve as keepers for a horizontal slide 7 and a rack 8. In the machine referred to these two parts are joined together forming one and the same piece. A bracket 9, attached to the slide 7, carries a spring clip 10 which holds the stencil 11 which is being cut. The rack 8 is fed to the left by a pinion 12 which is loose on a shaft 13. The pinion is provided with a disk 14 and there is an arm 15 on the front end of the shaft 13 which carries a spring plunger 16. This plunger is adapted to enter one of a series of holes 17 in the disk 14 and thereby lock the pinion to the shaft so that as the shaft 13 is revolved in the proper direction the rack will be fed to the left—the pin 16 being withdrawn to return the rack to normal starting position. The shaft 13 is journaled in a pair of brackets 18 which extend out from the bed and it has at its rear end a ratchet wheel 19. A feed shaft 20 which is in line with the shaft 13 carries an arm 21 having a pawl 22. The detailed construction and connections of the stencil machine are not shown—suffice it to say that the index wheel 4 is turned to bring the desired punch 3 over the stencil; the punch is then driven and on its return movement the feed shaft 20 is rocked so that the ratchet wheel 19 is moved one tooth and the shaft 13 is thereby turned a little and the stencil fed along so that the next punch which is driven will be stamped into the stencil along side of the previously punched characters.

Here is where my device is introduced. The rack which, in the machine referred to, is in one piece, I cut in two, forming the slide 7 and rack 8, as already pointed out. These parts I join by a bar 23 which is secured to the slide 7 and which is adapted to slide in a groove 24 of the rack 8—it being held by two keepers 25 and 26. This, in reality gives the effect of a telescoping rack

and slide. The two parts are joined by a variable connection which consists of a bell crank 27, pivoted to the keeper 25 which extends downward to support said bell crank 5 and a connecting link 28 which is pivotally attached to a block 29 secured to the slide 7. The lower arm of the bell crank 27 has a roll 30 which is adapted to travel in a channel 31 of an arm 32, the right hand end of said arm 10 being pivoted to a bracket plate 33 which is secured to the front side of the depending portion 5 of the main frame 1. The plate 33 is provided with a series of holes 34 and a pin 35 is adapted to hold the left end of 15 the arm 32 at any desired elevation.

It is evident from the foregoing construction that when the pin 35 is in the lower hole, as shown in Fig. 1, that the channel 31 will be horizontal and that the step-by-step 20 movement which is given to the rack 8 by the ratchet wheel 19 will be transmitted to the slide 7 and that the stencil will be fed a like amount, the same as though the parts 7 and 8 were integral. If, however, the left 25 end of the arm 32 be raised to the dotted line position shown in Fig. 1, as the rack 8 is carried to the left with the roll 30 traveling in the slot or channel 31 it will be carried upward with each movement of the 30 rack 8 and the slide 7 will be given a less movement and the letters of the stencil will be crowded closely together. By moving the pin 35 up one hole from the bottom one additional character can be put in and so on, 35 one additional character being added for each upward step of the arm 32. As the size of the stencil is fixed a forward limiting stop 36 is put in the frame to limit the slide 7 and this slide is formed with a shoulder 40 37 which limits the backward movement.

I claim:

1. In a stencil-cutting machine, a travel-

ing feed device; a stencil-carrying device; connections between said feed device and said stencil-carrying device; in combination 45 with means for giving said feed device a fixed step-by-step movement and means for simultaneously varying the length of the connections between said feed device and said stencil-carrying device. 50

2. In a stencil-cutting machine, the combination of a primary feed device with a stencil-carrying device—said devices being arranged to telescope or slide one on the other; means for giving said primary feed 55 device a fixed step-by-step movement; connections between said primary feed device and said stencil-carrying device which are adapted to reduce the movement of said stencil carrying device with relation to said 60 primary feed device and means for limiting the movement of said stencil-carrying device, whereby, with a fixed movement of said stencil-carrying device a variable movement is provided for said primary feed device. 65

3. In a stencil-cutting machine, the combination of the feed rack 8; bell crank 27 mounted on said rack; stencil-carrying slide 7; limiting stops 36 and 37; connecting link 28; the bracket plate 33 secured to the front 70 of said stencil-cutting machine; the swinging channel arm 32 pivoted to said plate; the pin 35 for holding one end of said channel arm in variable positions and the roll 30 secured to said bell crank and adapted to 75 slide in said channel arm, substantially as described and shown.

In testimony whereof I affix my signature in presence of two witnesses.

F. AMOS JOHNSON.
